SHUTTLE CHANGING LOOM

William W. Robertson, Worcester, Mass., assignor
to Crompton & Knowles Loom Works, Worcester, Mass., a corporation of Massachusetts

Application April 5, 1935, Serial No. 14,805

9 Claims. (Cl. 139—231)

This invention relates to improvements in shuttle changing looms and it is the general object of the invention to prevent the completion of a shuttle changing operation if the active depleted shuttle should fail to reach its shuttle box at the shuttle changing side of the loom.

In the type of loom to which my invention more particularly relates weft detecting mechanism is located on that side of the loom opposite the shuttle changing mechanism and acts upon substantial depletion of weft to initiate change in the shuttles. This change involves the stopping of the loom, the ejection of the depleted shuttle, the placing of a fresh reserve shuttle into active position, and restarting the loom. These several operations are accomplished by means of a so-called change shaft having cams which operate in proper sequence to perform the necessary operations. The loom is so controlled that it comes to rest during the replenishing period with the lay in back position. If under these conditions the active shuttle should fail to be boxed on the magazine side the shuttle changing mechanism might, unless otherwise controlled, place a reserve shuttle in the box so that the protector mechanism would be placed to permit resumption of weaving. A shuttle smash would result due to the fact that the depleted shuttle is still in the shed. It is an important object of my present invention to prevent the shuttle changing mechanism from placing a reserve shuttle in the shuttle box when the active depleted shuttle fails to be correctly boxed.

Should the active depleted shuttle remain in the shed it is also desirable to prevent restarting of the loom and it is a further object of my invention to provide loom starting mechanism which can be disabled whenever the active shuttle fails to reach its shuttle box on the shuttle changing side of the loom.

Shuttle changing mechanisms of the type to be described hereinafter include a conveyor which receives a reserve shuttle from the magazine and then moves rearwardly to place the shuttle in a shuttle box on the lay. It is a further object of my invention to utilize the movements of the conveyor to complete the control of the shuttle changing mechanism which is initiated by the protector mechanism. The conveyor may if desired supply the actuating force which disables the restarting mechanism for the loom. While the invention is set forth in connection with a so-called double shuttle loom having two active shuttles which are picked together yet it is to be understood that certain features are equally ap-

plicable to a loom operating with a single active shuttle, or a loom having several weaving shuttles which are active one at a time.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an end elevation of a loom having my invention applied thereto, showing the parts in the position they normally assume at the beginning of a shuttle changing operation.

Fig. 2 is a view similar to a portion of Fig. 1 but with the conveyors indicated in the three different positions which they assume during a normal shuttle changing operation.

Fig. 3 is a view similar to Fig. 2 but with the conveyors shown in the position they assume when shuttle change is to be arrested due to failure of an active shuttle to be correctly boxed.

Fig. 4 is an enlarged rear elevation taken in the direction of arrow 4, Fig. 1.

Fig. 5 is an enlarged end elevation of part of the structure shown in Fig. 2.

Fig. 6 is a detail horizontal section on line 6—6 of Fig. 5.

Fig. 7 is an enlarged front elevation looking in the direction of arrow 7, Fig. 3.

Fig. 8 is a side elevation looking in the direction of arrow 8, Fig. 7.

Fig. 9 is a detail vertical section on line 9—9 of Fig. 7, and

Fig. 10 is a detailed plan view of the protector control taken in the direction of arrow 10, Fig. 1.

Referring to the drawings, the loom frame 10 supports a lay 11 having upper and lower shuttle boxes 12 and 13, respectively. These boxes are arranged to receive upper and lower active weaving shuttles S and S', respectively, which are picked at the same time, preferably together so that both shuttles will be at the magazine side of the loom at the same time. Each shuttle box has a binder 14 to coat with protector fingers 15 to position knock-off daggers 16 in the usual manner. That part of the protector mechanism which actually stops the loom upon failure of either shuttle to be boxed has been omitted from the drawings since such structure is well understood and of itself forms no part of the present invention. During loom operation the lay swings back and forth around its rocker shaft 17 in the usual manner, the shuttles being picked as the lay reaches mid-point on its backward stroke.

An end frame 20 is spaced from the adjacent loom side and supports front and back magazines 21 and 22 which supply reserve shuttles for the lower and upper shuttle boxes 13 and 12, respectively. As shown more particularly in Fig. 2 each magazine has a shuttle support 23 normally positioned to support all of the reserve shuttles thereabove but movable forwardly to release the bottom-most shuttle carried by the magazine. The magazines may carry shuttles all of the same or different kinds.

In order that the reserve shuttles may be conveyed from the magazine rearwardly toward the lay when the latter is in back position at rest, there may be provided a pair of conveyors 25 and 26 cooperating, respectively, with the front and back magazines. Each conveyor carries a shuttle receiving shelf 27 and has a trip 28 to engage the corresponding bobbin support 23. The conveyors 25 and 26 are mounted on levers 30 and 31, respectively, both movable about a fixed loom carried pivot 32. Relatively heavy springs 33 tend to move the conveyors rearwardly toward the lay, such movement being controlled by the cams shown in Figs. 1 and 2. Lever 30 is attached by means of a connector 35 to a cam lever 36 controlled by cam 37 on the change shaft 38, while the other lever 31 is connected by a rod 39 to a second cam lever 40 controlled by a second cam 41 also on the change shaft. The lower conveyor has the greater travel because of the location of the associated magazine and its cam 37 is therefore larger than the cam 41.

In the operation of the mechanism thus far described the conveyors will be normally in the position shown in Fig. 1, and at the beginning of the shuttle changing operation the lay will be brought to rest in the rear position as indicated in that figure. The change shaft 38 will start rotating in the direction of arrow A to move levers 36 and 40 forwardly a slight amount sufficient to move the shuttle supports 23 from the full to the dot and dash line position shown in Fig. 2. The conveyors will move during this shuttle releasing movement to the dot and dash line positions shown in Fig. 2, after which continued running of the loom will first eject the depleted shuttles in the shuttle boxes during the time that the dwells 45 control the levers 36 and 40. After the active shuttles are ejected by mechanism not shown but well understood the cams will present the inclined surfaces 46 to controlling position, whereupon the springs 33 will move the conveyors rearwardly to the dotted line position shown in Fig. 2, thereby carrying the reserve shuttles previously received from the magazines toward the lay. The box front 47 will remain raised to permit entry of the fresh shuttles into their respective shuttle boxes.

After the fresh shuttles are correctly boxed a cam 48 on the shaft 38 will act to restart the loom and weaving will be resumed in the usual manner. The mechanism thus far described may be of known construction and except for the control exercised by the restarting cam 48 may operate in the usual manner.

The description already given is that which is normal and may properly take place when both active shuttles reach their shuttle boxes so that they may be properly ejected. It occasionally happens, however, that one or the other of these active shuttles fails to be boxed after the shuttle changing operation has been initiated, in which case the lay would come to rest in rear position

and fresh shuttles placed into the boxes, thereby moving the protector mechanism to running position to cause a smash. In order to prevent the conveyors from placing shuttles in the shuttle boxes unless the latter has received the depleted shuttles I provide mechanism operable preferably through the protector fingers to arrest movements of the conveyors.

As shown more particularly in Figs. 1 and 10, the lower dagger corresponding to the lower shuttle box 13 has movable therewith a depressing finger 50 which overhangs a plate 51 movable about a fixed pivot 52. The upper dagger also has a depressing finger 53 in position to engage the plate 51. The latter may be inclined downwardly and forwardly as at 54 so as not to interfere with the normal operation of the protector mechanism as the latter approaches forward position.

The plate 51 has an arm 55 movable therewith and operative through a nut 56 to hold a transmitting rod 57 rearwardly whenever plate 51 is held depressed by either of the fingers 50 or 53. The rod 57 is surrounded by a light spring 58 bearing against the lower part of arm 55 and providing a yielding connection between the arm 55 and the rod 57.

The rod 57 extends forwardly and is pivotally connected to a lever arm 58 fastened to a short shaft 59 extending through and supported by a hook arm 60. The latter is pivoted as at 61 to a stand 62 supported by the end frame 20. The outer end of shaft 59 has fastened thereto a hook 63 having a head 64 of sufficient breadth to engage two opposing lugs 65, one on each of the conveyor levers 30 and 31. The arm 60 carries a stop screw 66 to limit movement of arm 58 relatively to the arm 60 in a left hand direction as viewed in Fig. 5. The hook 63 is provided with a cam lug 67 having a surface 68 which is concentric with the axis 32 when the hook is in normal position and a rear surface 69 to effect resetting.

In the operation of that part of the invention already described the plate 51 and hook 63 will normally be in the position shown in Fig. 1, and so long as the active shuttles are properly boxed the depressing fingers 50 and 53 will be held elevated. If, however, either of the active shuttles fails to be correctly boxed following the initiation of a shuttle changing operation the corresponding protector finger will assume the in or stopping position with resultant lowering of the associated depressing finger. The plate 51 will therefore be held down to cause the depending arm 55 to remain in right hand position. During the short forward movement of the conveyor already described the concentric surface 68 will engage a lug 70 carried by one of the conveyor levers, 30 as shown herein, to hold the hook and connected parts against substantial vibration. Surface 68 will ordinarily be held against the lug 70 by a relatively light spring 71 which is weak enough to be overpowered by the depressing fingers 50 and 53.

As the conveyor levers start their rearward movement the lug 70 will reach the end of cam face 68 before the lugs 65 reach the hook head, thereby permitting upward movement of the hook during a normal shuttle changing beat to clear lugs 65. With the hook down, however, it will be engaged by the lugs 65 and moved from the full to the dotted line position shown in Fig. 3, thereby rocking hook arm 60 to the right as viewed in Fig. 5. This relation of parts is reached

when the conveyors in their rearward movement assume the position indicated in dotted lines in Fig. 3. Further rearward movement of the hook and therefore the conveyors is prevented by engagement of a finger 75 movable with lever 60 and a stop screw 76 supported by the bracket 62. A second stop screw 77 may also be employed to limit angular movement of the lever 60 in a left hand direction as viewed in Fig. 1. The 10 shuttle changing operation will therefore be arrested.

In addition to preventing operation of the conveyors it is also desirable to keep the loom at rest until the weaver can take from the shed the active shuttle which was not properly boxed. In 15 order to accomplish this result I provide means for preventing restarting of the loom. The cam 48 coacts with lever 80 movable about a fixed pivot 81 and having an upstanding finger 82 to 20 which is attached a tension spring 83. The latter is connected to the bottom of a bar 84 having a slot 85 to receive a pin 86 carried by arm 87 of the lever 80. The slot and spring provide a giveaway connection between the cam and the 25 bar 84.

The upper end of bar 84 has a shoulder 88 lying under a web 89 of a yoke 90 through which the upper end 91 of the bar passes. The yoke guides the bar and is of sufficient width to permit said bar to move far enough to the right from the position shown in Fig. 9 so that the shoulder 88 will be out of vertical alignment with the web 89.

The yoke has a hub 92 fastened to a restarting shaft 93 journaled in bearings 94 and 95, respectively, carried by the loom frame. A restarting arm 96 secured to the shaft 93 is attached to an upwardly extending rod 97 which when elevated acts through a shipper 98 to restart the 40 loom.

The restarting operation is operated by the cam 48 and if the transfer has been normal the cam, turning in the direction of arrow B, Fig. 3, will rock the lever 80 in a clockwise direction around the axis 81, causing the spring 83 to elevate the bar 84 to effect rocking of the web 89 and hub 92 by a force transmitted through the shoulder 88. This results in rocking of the shaft 93 which by the connection shown at the right hand side of Fig. 1 moves the shipper 98 to restart the loom.

Should the shuttle changing operation be interrupted as already described, I provide mechanism to prevent rocking of shaft 93. This result is accomplished by a rod 100 pivoted to the upper end of hook arm 60, see Fig. 3, and having the forward end thereof slotted as at 101 to receive a reduced upper end 91 of the bar 84, see Fig. 8. The spring 83 normally holds the shoulder 88 in operative position as shown in Fig. 9 but when the conveyors in the first part of their rearward movement move the hook rearwardly, the attendant rocking of arm 60 will move the rod 100 rearwardly from the full to the dotted line position shown in Fig. 3. Operation of the lever 80 by the cam at the conclusion of the shuttle changing period will therefore result in an idle upward movement of bar 84 and the shaft 93 will remain at rest to prevent the loom from 70 restarting.

During a normal transfer when the conveyor levers 30 and 31 move to their full rearward position indicated in dotted lines in Fig. 2 the hook will be raised by spring 71 by an amount limited by the stop screw 66. As the conveyor

levers move forwardly at the conclusion of the shuttle inserting operation the lug 70 will move against the cam face 69 and depress the hook so that the latter will be normally in the path of the lug 65.

From the foregoing it will be seen that I have provided a simple control for the shuttle changing mechanism wherein failure of an active shuttle to reach its shuttle box on the magazine side of the loom is effective to prevent rearward movement of the conveyors toward the lay. It will also be seen that inability of the conveyors to move rearwardly beyond the dotted position shown in Fig. 3 results in disabling the restarting mechanism and although the change shaft completes its rotation, there is nevertheless no opportunity for it to rock the shaft 93 and restart the loom if the shuttle changing operation has been interrupted.

Having thus described my invention it will be seen that changes and modifications may be made therein by those skilled in the art without departing from the spirit and scope of the invention and I do not wish to be limited to the details herein disclosed, but what I claim is:

1. In a shuttle changing loom which comes to rest with the lay in rear position, during the shuttle changing period, a pair of shuttle boxes stationary on the lay, a protector finger for each shuttle box, each finger movable to stopping position when the corresponding box is unoccupied by a shuttle, means to expel depleted shuttles from the shuttle boxes, two shuttle changing mechanisms each effective to convey a reserve shuttle to one of the shuttle boxes during the shuttle changing period after the depleted shuttles are expelled from the shuttle boxes, preventer means normally placed to prevent operation of both the shuttle changing mechanisms, and control connections between the protector fingers and the preventer means to render the latter operative to prevent operation of both shuttle changing mechanisms when either protector finger is in stopping position at the beginning of a shuttle changing operation.

2. In a shuttle changing loom having a lay with a shuttle box stationary thereon to receive a depleted shuttle and later receive a reserve shuttle during the shuttle changing period, protector mechanism to be positioned by a depleted shuttle in the shuttle box, means to expel a depleted shuttle from the shuttle box, shuttle changing mechanism to place a reserve shuttle into the box, a controller for the shuttle changing mechanism capable of preventing operation of the latter, and means interposed between the protector mechanism and the controller mechanism effective to move the latter by a force derived from the protector mechanism into position to prevent operation of the shuttle changing mechanism.

3. In a shuttle changing loom having a lay with a shuttle box stationary thereon to receive a depleted shuttle and thereafter receive a reserve shuttle during the shuttle changing period, a protector finger to be moved by the depleted shuttle, a shuttle changer normally operative to place a reserve shuttle into the shuttle box during the shuttle changing period, a preventer to arrest operation of the shuttle changer, and control connections between the protector finger and the preventer means to effect positioning of the latter to arrest operation of the shuttle changer by a force derived from the protector finger when the shuttle box is unoccupied by a depleted shuttle.

4. In a shuttle changing loom having a lay with a shuttle box stationary thereon to receive a depleted shuttle and thereafter receive a reserve shuttle during the shuttle changing period, a protector finger movable to stopping position when the depleted shuttle fails to reach the shuttle box and movable to running position when the depleted shuttle enters the shuttle box, a shuttle changer to place a reserve shuttle into the shuttle box, and a controller for the shuttle changer movable into position to prevent operation thereof by the protector finger when the latter moves to stopping position due to non-arrival of the depleted shuttle in the shuttle box.
5. In a shuttle changing loom having a shuttle box to receive a depleted shuttle and thereafter receive a reserve shuttle during the shuttle changing period, a protector finger movable to stopping position when the depleted shuttle fails to reach the shuttle box and movable to running position when the depleted shuttle enters the shuttle box, a conveyor to move a reserve shuttle toward the shuttle box, a lock for the conveyor, and connections between the protector finger and lock effective by a force derived from the protector finger when the latter moves to stopping position due to non-arrival of the depleted shuttle in the shuttle box to move the lock into position to arrest movement of the conveyor.
6. In a shuttle changing loom which is at rest during the shuttle changing period, a lay to be stationary in rearward position during the shuttle changing period, a pair of shuttle boxes at one end of the lay, a protector finger for each shuttle box movable to stopping position when the corresponding shuttle box is unoccupied by a shuttle, a pair of shuttle conveyor mechanisms both operative at the same time to place a reserve shuttle in each shuttle box, and means controlled by the protector fingers to prevent operation of both shuttle conveyor mechanisms when either protector finger is in stopping position at the beginning of a shuttle changing period.
7. In a shuttle changing loom having a lay

which is at rest during the shuttle changing period, a pair of shuttle boxes at one end of the lay, a protector finger for each box, each finger movable to stopping position when the corresponding shuttle box is unoccupied, conveyor means to convey two reserve shuttles to the lay, one for each shuttle box, during the shuttle changing period, and means controlled by the protector fingers and operative when either protector finger is in stopping position at the beginning of the shuttle changing period to prevent operation of the conveyor means.

8. In a shuttle changing loom which is at rest during the shuttle changing period, a pair of shuttle boxes at one end of the lay, a protector finger for each shuttle box, each finger movable to stopping position when the corresponding shuttle box is unoccupied by a shuttle, two magazines of reserve shuttles, a conveyor for each magazine to transfer a reserve shuttle from the corresponding magazine into one of the shuttle boxes on the lay during the shuttle changing period, and means controlled by the protector fingers and effective when either finger is in stopping position at the beginning of the shuttle changing period to prevent operation of both conveyors.

9. In a shuttle changing loom, which is at rest during the shuttle changing period, a pair of shuttle boxes at one end of the lay, a protector finger for each shuttle box, each finger movable to stopping position when the corresponding box is unoccupied by a shuttle, two separate shuttle conveyor mechanisms each effective to move a reserve shuttle into a shuttle box, means normally operative to cause both of said mechanisms to operate together, and control means for the shuttle conveyor mechanism operatively related to the protector fingers and effective when either protector finger is in stopping position at the beginning of a shuttle changing period to prevent operation of both shuttle conveyor mechanisms.

WILLIAM W. ROBERTSON.
